UNITED STATES PATENT OFFICE

MARTIN WINTERHALTER, OF HALLE-ON-THE-SAALE, GERMANY

SLIDING CLASP FASTENING

No Drawing. Application filed September 6, 1928, Serial No. 304,383, and in Germany October 24, 1927.

The tapes used for carrying the locking members in sliding clasp fastenings have one longitudinal edge provided with a thickening, on which the locking members are clamped. This thickening is usually formed by two separate cords sewn to the tape. If the cord and the tape be made of equal length and the tape be subsequently sewn to a garment or the like, the two rows of locking members to be closed by the sliding member will diverge and the sliding member will be very stiff to move. In order to overcome this difficulty, it has already been proposed in German Patent Specification 325390 to make the cords shorter than the bands. This, however, has the effect of causing small puckers to form in the part of the band bordered by the cords and these puckers offer resistance to the sliding member, detrimentally affecting its freedom of motion. A further disadvantage in the latter case is that, as the band and the cords, owing to their being sewn together, represent organically independent members, the cords are alone stressed when the locking members are clamped on. The cords, however, only have their original length and a corresponding closeness of texture. The cords would on the one hand be improved as supporting members of their density could be increased. It would be a further advantage to make use of the band itself as well for supporting the locking members. In doing this, however, the freedom of motion of the sliding member must not be adversely affected, care being taken that the disadvantage of the puckering in the band in the vicinity of the thickened edge is avoided and that the rows of locking members face one another. The problem thus set out is solved by the present invention in the first place by the band and the cord being woven together so that they form an organic whole. In addition to this the cords and preferably the adjacent warp threads of the band are specially

stretched during the weaving operation. When the cords are made in the form of a hollow tubular woven fabric with special inserted threads, both the inserted threads and the threads of the tubular fabric must be subjected to the stretching operation. In a corresponding manner the thickened part, when made of a solid woven fabric, must be stretched as a whole.

This stretching results in greater density within the cords or, if the density remains the same, in reduced circumference, which is of advantage in clamping on the locking members. The density is still further increased by the contraction following the cessation of the stretching operation. At the same time by this construction the desired rounding of the band is effected, that is the converging of the edges of the band which are bordered with cord.

Hence, the weaving and stretching are essential for the method of manufacture according to the invention, that is for the greater resistance of the thickened edge and for producing the round shape. Should the latter effect not be obtainable in a sufficient degree through the stretching process the parts of the band remote from the thickened edge may be stretched in the finished woven material, for instance by winding the same on to conical rollers.

What I claim is:

1. A method of manufacturing bands double corded at one of their edges for sliding clasp fastenings, consisting in weaving so the bands and the cords together and stretching the cords alone during the weaving operation, as and for the purpose set forth.

2. A method of manufacturing bands double corded at one of their edges for sliding clasp fastenings, consisting in weaving the bands and the cords together and stretching only the cords and the adjacent warp threads of the band during the weaving operation, as and for the purpose set forth.

3. A method of manufacturing bands corded at one of their edges for sliding clasp fastenings, consisting in weaving the bands and two cords alone together at said edge of each band, stretching the cords during the weaving operation and subsequently stretching the parts of the band remote from the corded edge without stretching the main portions thereof, as and for the purpose set forth.
- 10 In testimony whereof I have signed my name to this specification.

MARTIN WINTERHALTER.
